UNITED STATES PATENT OFFICE.

WILLARD T. SEARS, OF PHILADELPHIA, PENNSYLVANIA, ASSIGNOR TO NILES-BEMENT-POND COMPANY, OF JERSEY CITY, NEW JERSEY.

DROP-HAMMER.

No. 882,588.

Specification of Letters Patent.

Patented March 24, 1908.

Application filed December 11, 1907. Serial No. 406,005.

To all whom it may concern:

Be it known that I, WILLARD T. SEARS, a citizen of the United States, residing at Philadelphia, Philadelphia county, Pennsylvania, 5 have invented certain new and useful Improvements in Drop-Hammers, of which the following is a specification.

This invention pertains to improvements in that class of drop hammers in which the 10 hammer is elevated by the action of a pair of pinching rolls engaging a stem attached to the hammer, the pinching and releasing action of the rolls upon the stem being under the control of a treadle. The stem attached to the hammer may be a rod, strap, or board, preferably the latter.

The improvements will be readily understood from the following description taken in connection with the accompanying drawings in which:—

Figure 1 is a front elevation of a drop hammer exemplifying my improvements: Fig. 2 a side elevation of the same: Fig. 3 a vertical section in the plane of line *b* of Figs. 1 and 4: 25 Fig. 4 a horizontal section in the plane of line *a* of Figs. 1 and 3: Fig. 5 a rear elevation of the valvechest, with the cover removed: and Fig. 6 a front elevation of the upper end of the treadle-rod controlling the valve.

30 Various scales of dimensions are employed in the several figures.

In the drawings:—1, indicates the anvil: 2, the uprights: 3, the top housings: 4, the hammer guided vertically by the uprights: 35 5, the stem, illustrated as a board having its lower end secured to the hammer: 6, one of the pinching rolls journaled in the top housing and occupying a fixed position therein: 7, the second pinching roll: 8, a pulley for 40 giving motion to the rolls: 9, the trigger pivoted to one of the uprights and adapted to engage under a projection of the hammer and support the hammer in elevated position at a height according to the adjustment of 45 the trigger: 10, the rod for controlling the opening and closing of the rolls: 11, the treadle: 12, the spring for holding the treadle in upper position: 13, the rod connecting the treadle with the trigger so that depressing 50 the treadle releases the trigger: 14, a lever pivoted to the foot of one of the uprights and having its inner end under and supporting the controlling rod 10, the outer end of this lever being heavier than the inner end: 15, a

link connecting the treadle and the outer end 55 of lever 14, this link being of a character not capable of transmitting strain compressively, a strap form of link being illustrated: 16, a tappet rigidly secured to but adjustable on controlling rod 10 and adapted to be engaged by a lifting lug on the hammer: and 17, a spring coöperating with trigger-rod 13 and trigger 9 to permit the trigger to have releasing movement independent of treadle movement.

65 All of the parts thus far described are substantially as usual in this general class of drop hammers and are subject to the usual modification in the construction and arrangement of those parts.

70 Continuing with the drawings:—18, indicates a bellcrank lever pivoted in the top housing, its vertical short arm being bifurcated and carrying the bearings of pinching roll 7, its horizontal arm being mortised for 75 the free passage of the board forming the stem of the hammer: 19, a fluid-pressure cylinder supported by the top housing under the outer end of the bellcrank lever: 20, the piston of this cylinder: 21, the piston-rod, linked to the outer end of the bellcrank lever: 22, the valvechest of the cylinder: 23, the fluid inlet to the valvechest the fluid being, preferably, compressed air and herein-after referred to as air: 24, a valve disposed 80 in the valvechest, this valve being of ordinary D-type and coöperating with an exhaust port and with ports communicating with each end, respectively, of the cylinder: 25, the exhaust outlet: 26, a roller on the 85 outer end of the valve-stem, this roller bearing against the side of controlling rod 10: 27, a spring engaging the valve-stem and urging it toward the controlling rod: and 28, a cam 90 formed on the side of controlling rod 10 where it engages the roller 26, the cam being of such form that one vertical position of the controlling rod forces the valve to one extreme position, while another vertical position of the controlling rod permits the spring 95 to move the valve to its other extreme position.

100 In Fig. 3 the piston is in upper position and the rolls are so separated as to be free of the hammer stem. If air be exhausted from below the piston and be admitted under pressure above the piston then the piston will move down and cause the rolls to pinch the

hammer-stem, the rotation of the rolls causing the hammer to be lifted.

In Fig. 4 the valve is in one extreme position, as forced there by the cam on controlling rod 10, and the spring is under compression. The left-hand port, which is the one leading to the lower end of the cylinder, is in communication with the valve chest so as to admit air under the piston, while the right hand port, which is the one leading to the top of the cylinder, is in communication with the exhaust. Such is the condition when the hammer-stem is free of the pinching rolls and when the controlling rod is in its upper position, and such is the condition of parts in Fig. 1.

In Fig. 1 the hammer is in upper position and held there by the trigger 9. The trigger may have its pivot located at high or low points to bring about selections for the top position for the hammer, corresponding adjustments being made at the connection between the trigger and the trigger rod 13, and between the tappet and the controlling rod 10. In Fig. 1 the trigger-held hammer supports controlling rod 10 in upper position. If, now, the treadle be depressed, the trigger will release from the hammer and the hammer will fall and deliver its blow, the depression of the treadle straightening link 15 and maintaining the support of the controlling rod. The hammer remains down so long as the treadle remains depressed. If, now, the treadle be allowed to rise then controlling rod 10 will descend by its own weight and bring a shallow part of its cam 28 to the valve stem roller, thus permitting spring 27 to move the valve to position to admit air over the piston and to exhaust the air from below the piston. The piston now descends and the rolls pinch the hammer-stem and the hammer is elevated. The release of the treadle causes the trigger to go to engaging position but the yielding of spring 17 permits the hammer to displace the trigger which promptly returns to position for engagement with the hammer. The lifting lug on the hammer strikes the tappet and lifts controlling rod 10 and, in an obvious manner, brings about the separation of the rolls thus freeing the hammer-stem from their influence. The hammer, thus otherwise free to fall, is arrested by the trigger and upheld thereby till the treadle is again depressed. The hammer is thus allowed to fall at each depression of the treadle and is lifted at each release of the treadle.

I claim:

1. A drop hammer comprising an anvil, vertical guides, a hammer fitted to work in the guides, a stem projecting upward from the hammer, a pair of pinching rolls adapted for rotation in contact with the stem and adapted for relative movement to and from each other so as to be in or out of contact with the stem, a fluid-pressure cylinder, a

piston therein, a connection between said piston and one of said pinch rolls to cause the movement of the piston to bring about the opening and closing of the rolls upon the stem, a valve for controlling the flow of fluid to and from the cylinder, a treadle, and connections between the treadle and valve for controlling the movements of the valve, combined substantially as set forth. 70

2. A drop hammer comprising an anvil, vertical guides, a hammer fitted to work in the guides, a stem projecting upward from the hammer, a pair of pinching rolls adapted for rotation in contact with the stem and adapted for relative movement to and from each other so as to be in or out of contact with the stem, a fluid-pressure cylinder, a piston therein, a connection between said piston and one of said pinching rolls to cause the movement of the piston to bring about 85 the opening and closing of the rolls upon the stem, a valve for controlling the flow of fluid to and from the cylinder, a treadle, connections between the treadle and valve for controlling the movements of the valve, and tappet mechanism connected with the hammer and valve to cause the hammer to act on the valve at the upper end of its stroke, combined substantially as set forth. 90

3. A drop hammer comprising an anvil, vertical guides, a hammer fitted to work in the guides, a stem projecting upward from the hammer, a pair of pinching rolls adapted for rotation in contact with the stem and adapted for relative movement to and from each other so as to be in or out of contact with the stem, a fluid-pressure cylinder, a piston therein, a connection between said piston and one of said pinching rolls to cause the movement of the piston to bring about 100 the opening and closing of the rolls upon the stem, a valve for controlling the flow of fluid to and from the cylinder, a treadle, a controlling rod extending vertically and having connection with the treadle, and a cam carried by the controlling rod and co-operating with the stem of the valve in such manner that the vertical movements of the controlling rod bring about the shifting of the valve, combined substantially as set forth. 110

4. A drop hammer comprising an anvil, vertical guides, a hammer fitted to work in the guides, a stem projecting upward from the hammer, a pair of pinching rolls adapted for rotation in contact with the stem and adapted for relative movement to and from each other so as to be in or out of contact with the stem, a fluid-pressure cylinder, a piston therein, a connection between said piston and one of said pinching rolls to cause 125 the movement of the piston to bring about the opening and closing of the rolls upon the stem, a valve for controlling the flow of fluid to and from the cylinder, a treadle, a controlling rod extending vertically and having 130

connection with the treadle, a cam carried by the controlling rod and coöperating with the stem of the valve in such manner that the vertical movements of the controlling rod bring about the shifting of the valve, and tappet mechanism connected with the hammer and controlling rod to cause the hammer

to lift the controlling rod and shift the valve at the upper end of the hammer stroke, combined substantially as set forth.
